LUMINAIRE

Charles P. Breed, Alexandria, Va., and Melvin R. Anderson, Avon Lake, Ohio, assignors to Westinghouse Electric Corporation

Filed Dec. 5, 1969, Ser. No. 20,377

Term of patent 14 years

Int. Cl. D26—03, 05
U.S. Cl. D48—31

FIG. 1 is a side elevation of a luminaire embodying our new design.

FIG. 2 is a bottom perspective view of the luminaire as shown in FIG. 1 on an enlarged scale.

FIG. 3 is a second side elevation of the luminaire.

FIG. 4 is a top perspective view of the luminaire as shown in FIG. 3 on an enlarged scale.

The supports for the luminaire shown in broken lines form no part of this invention and are for purposes of illustrating the environment only.

We claim:

The ornamental design for a luminaire, substantially as shown and described.
